UNITED STATES PATENT OFFICE.

ANNA R. POTTS AND JESSE M. CROW, OF SAN DIEGO, CALIFORNIA.

INVALID'S-BED ATTACHMENT.

1,215,850.

Specification of Letters Patent. Patented Feb. 13, 1917.

Application filed July 15, 1914. Serial No. 851,080.

To all whom it may concern:

Be it known that we, ANNA R. POTTS and JESSE M. CROW, residents of San Diego, in the county of San Diego and State of California, have invented certain new and useful Improvements in Invalids'-Bed Attachments, of which the following is a specification.

Our invention relates to an attachment for beds for the use of invalids, which facilitates their movement into various positions and provides a table for writing or reading purposes in connection therewith.

The objects of our invention are, first, to provide a device of this class, which is adjustable throughout for different sized bed frames and for different sized invalids, second, to provide a device of this class which combines an adjustable table, back rest or support and exerciser for invalids, third, to provide such a device that is simple of construction, durable and sanitary, fourth, to provide such a device that is readily made applicable for different sized and shaped beds or bed frames and, fifth, to provide a back rest that is automatic with the movement of the invalid.

With these and other objects in view as will appear hereinafter our invention consists of certain novel features of construction, combination and arrangement of parts as will be hereinafter described in detail and particularly set forth in the appended claims, reference being had to the accompanying drawings and to the characters of reference thereon which form a part of this specification, in which:

Figure 1 is a perspective view of our device, complete, shown mounted on a fragmentary portion of the side rails of a bed frame, Fig. 2 is an end view thereof, Fig. 3 is a detailed side elevational view of the back rest clamp with parts broken away and in section to facilitate the illustration, Fig. 4 is a detailed side and sectional view of one of the means for attaching our device to the bed frame and Fig. 5 is a detailed side view of a fragmentary portion of the table and its support.

Similar characters of reference refer to similar parts throughout the several views.

The bed frame attachments 1, vertical supports 2, top horizontal support 3, swing 4, table 5, table support 6, back rest 7, lower back rest support 8, upper back rest support

9 and back rest clamp 10 constitute the principal parts of our invalid's bed attachment.

The bed frame attachments 1 are composed of pieces of channel iron which are adapted to fit over the vertical member of the bed angle or over the side of a bed providing the bed has other side pieces besides angle iron. Mounted vertically on the middle of this channel iron is a tube 1^b, which extends upwardly to approximately the height of the top of the mattress on the bed and this tube is supported by means of a brace 1^c extending from the end of the angle iron to near the top of this tube 1^b. Inside this tube 1^b is provided a compression spring 1^d and mounted over said tube 1^b is the latch 1^e, which extends down through the upper horizontal member of the channel iron and rests against the side of the vertical side piece A of the bed frame. In case, however, this side rail A of the bed is reversed so that the horizontal member is above, as shown in Fig. 4 of the drawings, there is provided a special clamp consisting of the piece 1^f, which extends over the horizontal member of the side rail A and through a slot 1^g in the channel iron and extends downwardly spaced apart from the vertical member of said side rail, and another U shaped piece 1^h which fits over the lower side of the vertical member of said side rail and extends up between the said side rail and the extended piece 1^f. The two are clamped together by means of a thumb screw 1ⁱ the extended member of 1^f being slotted to allow for adjustment. Mounted in these bed frame attachments which are placed one on each side of the bed frame are the vertical supports 2, which are adapted to fit into the upper end of these tubes 1^b of these bed frame attachments. They are each provided adjacent to the top end of these tubes 1^b with a right angled extension consisting of a tube 2^a. In the lower surface of this tube 2^a is provided a spring 2^b, which fits in notches in the lower surface of the tube members 8 which fit into the tube 2^a and hold the same in its relative position thereto. Mounted between these two vertical supports 2 is the table 5, which is provided with lugs 5^a which fit loosely around the table support 6. This table support 6 consists of two tubes one of which is inserted inside of the other so that they telescope therein and are held in certain relative po-

95
100
105
110

sitions by means of a spring latch 6^a. This spring latch is shown best in Fig. 5 of the drawing. On the inner surface of the support 2 are provided a plurality of notches 2^c and the ends of the supports 6 are provided with an extended portion adapted to conform to the notches 2^c in the tubes so that when placed in said notches at their extended portion and then allowed to drop 10 into the narrow portion said notches and extended portions secure this support 6 in its position. This spring latch 6^a is provided with a downwardly extending tube 6^b and with a slot in its lower end adapted for the 15 table adjusting rod 5^a. This tube is also provided with a spring 6^c adapted to hold the table adjusting rod 5^a down so that the notches 5^b therein engage with the edge of the slot for adjusting the table to the proper 20 tilt on its support. This rod 5^a may be removed by releasing the spring latch 5^c, which engages with a notch around the surface of the pivot 5^d on one corner of the table 5. Mounted in the tops of these tubes 25 2 is the top horizontal support 3 which consists of three tubes 3, 3, and 3^a. The tubes 3 and 3 are L-shaped, one member of each of which extends into one of the tubes 2 and their other members extend into the tube 3^a so that the tubes 3 are telescopically 30 mounted in the tube 3^a to provide for adjustment of this bar for different width bed frames. This center piece 3^a is provided with a slot horizontally therein in the 35 middle thereof, which is adapted to conform to the vertical end of the support 9 so that when the support 9 is turned at right angles to its position, as shown in Fig. 1, it may be inserted into this slot to the position desired, there being several notches 9^a in the 40 end adapted for adjusting it relatively to said top horizontal support and when turned in the position as shown in Fig. 1 is held therein. Mounted on this top horizontal 45 support is a swing 4, which is composed of two short ropes or cables 4^a and a cross tube adapted for the hand hold of the invalid. This swing is for the purpose of the person taking hold of the same and raising himself 50 into the position desired. The support 9 is a tube from the notches downwardly and is provided on its inner surface with a spring 9^a which is attached to the tube at point 9^b and this tube 9^a is provided with a 55 slot in its under surface adapted for the screw 10^e of the back rest clamp 10 to slide therein. The back rest 7 consists of a plate composed of any suitable material and properly reinforced and it is pivotally mounted 60 upon the lower back rest support 8 so that it may be tilted into the position desired and held in such position by means of the clamp 10. The lower back rest support 8 consists of two L shaped tubes the one adapted 65 to telescope into the other to provide for

the adjustment for different width bed frames. On the back surface of the back rest 7 at its normally upper end are two notches similar to the notches 2^c in the tubes 2 into which are inserted the bolts 10^b in the clamp member 10^a as shown best in Fig. 3 then the whole of the clamp 10 is moved upwardly and a button which is pivotally mounted on the back rest 7 is turned against the end of the member 10^a of the clamp 10 which holds it in position. This clamp piece is provided with a small sleeve 10^d which is held in position by means of the bolt 10^e and between this sleeve 10^d and the annular portion of the piece 10^a the tube 9 is adapted to be inserted and the clamp piece 10 moved back and forth thereon when released, but it is held in certain relative positions to said tube 9 by means of the spring 10^f pressing the block 10^f against the tube forming a grip on 80 said tube and holding it in position when in use. This grip it will be noted is so constructed that when pressure is against the upper surface of the back rest the grip 10^f holds the clamp 10 in certain relative position to the tube 9, but when the pressure is relieved against the back rest 7 the tension spring 9^a pulls the top end of said back rest upwardly on the tube 9 so that when the invalid pulls himself up by means of the swing 4 the back rest 7 automatically moves with him and as soon as he rests against it the clamp 10 immediately engages with the tube and holds it in that certain position, however, if it is desired to hold the back rest in a certain position there is provided a key 10^g, which is provided with a cam surface so that when turned it locks said clamp rigidly to said tube 9, but when turned back releases said clamp from said tube. 95

Though we have shown and described a particular construction, combination and arrangement of parts we do not wish to be limited to this particular construction, combination and arrangement but desire to include in the purview of our invention the construction, combination and arrangement substantially as set forth in the appended claims. 105

It is obvious that with this construction there is provided a device which may be readily attached to a bed which provide comfort and ease whereby an invalid may change his position without the help of a nurse; that the device is adjustable throughout to provide for different width bed frames and it is applicable for different makes of bed frames; that the table for the use of the invalid may be raised, lowered and adjusted as desired; that the back rest may be adjusted to suit the invalid's comfort; that the parts consist principally of metal so that they are sanitary; that the device may be readily taken to pieces and packed into a compact form for moving if desired; that 115 120 125 130

the back rest is controlled by the pressure against its upper surface so that when the invalid desires to be raised slightly he may do so by simply pulling himself up by the swing 4 and the back rest moves with him and is held in position as soon as pressure is brought to bear against it.

Having thus described our invention what we claim as new and desire to secure by Letters Patent is:

1. In a bed attachment for invalids, the combination of readily attachable and detachable vertical supports, a horizontal bar telescopically mounted in the upper ends of said supports and a back rest adjustably mounted on said supports and said horizontal bar.

2. In a bed attachment for invalids, the combination of supports adapted to be readily secured to the sides of a bed frame, vertical supports mounted therein, a horizontal bar telescopically mounted in the upper ends of said supports and a back rest adjustably

mounted on said supports and said horizontal bar.

3. In a bed attachment for invalids, the combination of readily attachable and detachable vertical supports, a horizontal bar telescopically mounted in the upper ends of said supports, another horizontal bar mounted intermediate the ends of said supports, a back rest pivotally mounted on said last mentioned bar and means connecting the upper end of said back rest with said first mentioned bar tending to move said back rest to a vertical position when the weight is relieved therefrom.

In testimony whereof, we have hereunto subscribed our names in the presence of two subscribing witnesses.

ANNA R. POTTS.
JESSE M. CROW.
